MARKING AND SEALING TAG

Application filed January 8, 1929, Serial No. 331,038, and in the Netherlands January 14, 1928.

This invention relates to improvements in marking and sealing tags, especially adapted for use for attachment to the animals but also adapted for other similar uses.

5 The invention is more particularly concerned with tags of that type comprising a strip of metal adapted to be bent to form two arms and which is pointed at one end and adapted at that end to be bent at right angles 10 to the plane of the strip, the other end being formed with a slot through which the pointed end is passed and curled over on closing the tag by means of a pair of tongs or any other instrument.

15 Such tags are for example used as ear markers for slaughter-cattle, which prior to slaughter have been insured by some insurance company.

These tags may bear an identification mark 20 or number.

The tags are also used for living cattle as proof of examination and that they have been found free from tuberculosis or other disease.

It is clear that such tags should not possess 25 an irregular outline or be so formed as to catch in the branches of a tree, barbed wire or the like with the result that the animal's ear may be torn, the wound infected and the tag lost. Moreover such markers must be so 30 constructed as to prevent their misuse so that once opened they are irreparably damaged to such an extent that they are incapable of reuse.

The object of the invention is to provide 35 an improved form of tag which meets all these requirements.

According to the invention the tag is formed of a strip of sheet metal having at one end a point and at the other end a substantially circular head having a slot for the reception of the point; this slot, on one side of the strip is covered by a cap, which has a guiding face on its inner side for automatically curling the prong or point when the 45 tag is closed after the point has been passed through the slot and the invention consists essentially in that the dome-shaped cap of hard material is of substantially circular circumference and the correspondingly shaped 50 edge of the cap is folded over the periphery

of the head and against the underside of the strip in order to fix the cap to the strip; the head being connected to the body of the strip by a neck, the width of which is less than the diameter of the head.

55 It has been discovered that notwithstanding the fact that the rounded cap protects the curled point fully from uncurling by means of any tool, it is still possible in certain cases by careful operation to withdraw the point 60 from the slot by uncurling the point slowly, in such a way that the tag can be flattened and used again.

A further object of the invention is therefore to prevent this possibility and this is attained by weakening the metal of the strip 65 at certain points in such a way that if an attempt is made to forcibly open the tag it will be broken at one or other of these points. One or more incisions in the metal of the strip 70 may be made for this purpose which will break at that place, thus making the strip unfit for further use.

75 Preferably the tag is made with one or more of the following three features:

(a) The neck of the tag is weakened by an incision made in one of the faces of the metal strip,

(b) The point of the marker is weakened by an incision at some distance from the end 80 of the point, immediately below the portion which forms the curl,

(c) That part of the circular extremity 85 of the strip which houses the curl of the point is formed with two cuts one on either side of the slot and is further weakened by an incision extending from the base of one cut to that of the other and if desired by a hole, in such a way that the part situated between the two cuts, which houses the curl forms a lip which breaks if an attempt is made to withdraw the curl from the cap.

The invention is illustrated in the accompanying drawings in which:

Figures 1 and 2 are a plan and side elevation of a tag having the feature *a*.

Figures 3 and 4 are similar views of a tag having feature *b*.

Figures 5 and 6 are similar views having feature *c*, Figure 6 being partly in section.

and Figure 7 is a section of a tag to a larger scale provided with features *a*, *b* and *c* and in closed or sealed position.

1 indicates a sheet metal strip, which is formed at one end with a point 2 and at the opposite end with a substantially circular head which is provided with a slot 3, and to which head a substantially circular cap or housing 4 is fixed by folding the edge of the cap over and around the peripheral edge of the head and against the under side of the strip. The cap 4 has a dome 5 provided with a guiding face for curling and housing the point 2 when the tag is closed by pressing the ends of the two arms towards each other, after the point 2 has been passed through the slot 3.

6 indicates an incision in the metal of the neck, which incision diminishes the thickness of the metal and weakens it at this point.

At 8 is indicated an incision in the surface of the metal located at such a distance from the end of the point that the incision after the point is curled is positioned below and at one side of the curl.

10 and 11 indicate two cuts in that part of the head which form a part of the housing for the curl in the cap. As will be seen these cuts are made at the ends of the slot 3 and they extend toward the neck. A lip 9 is thus formed which must break off when any one attempts to draw the point out of the cap, and for this purpose it is also weakened at its foot by an incision 12 in the face of the metal, and an opening 13 is provided in the tag at a point in the neck or narrow end of the lip.

It is clear that any one or more of the features mentioned (*a*, *b* and *c*) may be applied to the same tag.

What we claim is:

1. A marking and sealing tag comprising a sheet metal strip having a narrowed point at one end and a substantially circular head at the opposite end provided with a slot for the reception of the point and a substantially circular cap on the head, covering the slot and having a continuous peripheral portion bent around the peripheral edge of the head.

50 2. A tag as claimed in claim 1, in which the strip is provided also with a lip extending to one side of the slot and on which the point of the strip bears when said point has been passed through the slot and bent and clenched under the cap.

3. A tag as claimed in claim 1, in which the strip is provided with a weakening incision near the point.

60 4. A tag as claimed in claim 1, in which the strip is provided also with a lip extending to one side of the slot and on which the point of the strip bears when said point has been passed through the slot and bent and clenched under the cap and the neck of said

lip is provided with a weakening opening.

In testimony whereof we have signed our names to this specification.

JOANNUS JACOBUS PERQUIN.
HENRI JACOBUS FRANCKEN.
